DESIGN FOR A COMBINED EARRING AND BARRETTE

Arno Wrazlowsky, New York, N. Y.

Application May 22, 1947, Serial No. 139,217

Term of patent 3½ years

(Cl. D45—9)

To all whom it may concern:

Be it known that I, Arno Wrazlowsky, a citizen of the United States of America, residing in New York city, county of New York, and State of New York, have invented a new, original, and ornamental Design for a Combined Earring and Barrette, of which the following is a specification, reference being had to the accompanying drawing, forming part thereof, wherein

bined earring and barrette shown in Figures 1 and 2.

I claim:

The ornamental design for a combined earring and barrette, substantially as shown.

ARNO WRAZLOWSKY.
